United States Patent Office.

JAMES JOREY, OF WESTVILLE, CONNECTICUT.

Letters Patent No. 74,829, dated February 25, 1868.

IMPROVEMENT IN HORSE-SHOES.

The Schedule referred to in these Letters Patent and making part of the same.

TO ALL WHOM IT MAY CONCERN:

Be it known that I, JAMES JOREY, of Westville, in the county of New Haven, and State of Connecticut, have invented a new and improved Horse-Shoe; and I do hereby declare that the following is a full, clear, and exact description thereof, which will enable those skilled in the art to make and use the same, reference being had to the accompanying drawings, forming part of this specification.

This invention relates to a new and improved horse-shoe of that class which are provided with removable or detachable calks.

The invention consists in having the calks constructed and applied to the shoe in such a manner that they may be not only detached from the shoe, but also reversed and secured thereto in such reversed position as to admit of a fresh cutting or sharp edge for the calks being obtained, the calks being constructed with two edges to obtain this result.

If necessary, or desired, one edge of the calks may be made sharp and the other comparatively blunt, so that a horse may, by a very simple adjustment of the calks, be provided with either sharp or blunt calks, be either sharp or "rough" shod, the latter condition being preferable when the roads are not very slippery or icy, and the former condition preferable when there is much ice. In the accompanying sheet of drawings—

Figure 1 is an inverted plan or under view of a horse-shoe provided with my improvement.

Figure 2, a vertical section of the same, taken in the line x x , fig. 1.

Similar letters of reference indicate corresponding parts.

A represents a horse-shoe, which may be constructed in the usual or in any proper manner, and B represents a toe-calk, which is secured to the front of the under side of the shoe by means of two screws, a a . This calk is constructed of a piece of flat steel, or a steel plate, having its front and rear parts, b b' , bent outward at right angles from the main portion, at opposite sides thereof, (see fig. 2,) so that when the part b is used for the tread-portion, the other part, b' , will be up behind the front part of the shoe.

By this means the calk is provided with two tread-portions, either of which may be used, as desired, so that when one becomes worn the other may be adapted for use by simply detaching and reversing the calk. And, if necessary, one part, b , of the calk may be made with a blunt edge, and the other part, b' , with a sharp edge, the blunt part b being preferable when the roads are not very slippery or icy, as they are not so liable to be affected by wear. Sharp calks soon wear blunt on hard-frozen ground, and become inefficient on ice.

My improvement, it will be seen, admits of the calks being readily adapted to suit the condition of the roads.

Heel-calks, C, may be constructed and applied to the shoe in substantially the same way as the toe-calks above described.

The bodies or main portions of all the calks may be fitted in recesses in the bottom of the shoe, in order to preserve the screws from undue strain, and to more firmly secure the calks to the shoe.

I do not claim a removable or detachable calk for a horse-shoe, for they have been previously used; but I do claim as new, and desire to secure by Letters Patent—

A calk for a horse-shoe provided with two edges, and constructed and applied to the shoe in such a manner that it may be detached and reversed and either edge adapted for use, as circumstances may require.

JAMES JOREY.
